COMBINATION LAWN EDGER AND TRENCHER HEADPIECE

William H. Schumacher, Oklahoma City, Okla.

Application August 13, 1957, Serial No. 47,354

Term of patent 7 years

(Cl. D40—1)

FIG. 1

FIG. 2

I claim:

The ornamental design for a combination lawn edger and trencher headpiece, substantially as shown.
